UNITED STATES PATENT OFFICE.

JOHN S. WORTH AND CHARLES B. FAIRWEATHER, OF COATESVILLE, PENNSYLVANIA, ASSIGNORS TO J. S. WORTH AND W. P. WORTH, OF COATESVILLE, PENNSYLVANIA.

BOILER-BRACE.

SPECIFICATION forming part of Letters Patent No. 699,999, dated May 13, 1902.

Application filed November 30, 1901. Serial No. 84,229. (No model.)

To all whom it may concern:

Be it known that we, JOHN S. WORTH and CHARLES B. FAIRWEATHER, citizens of the United States, and residents of Coatesville, Pennsylvania, have invented certain Improvements in Boiler-Braces, of which the following is a specification.

Our invention relates to certain improvements in braces for strengthening boilers and other sheet iron or steel structures.

The main object of our invention is to economically manufacture such a brace and provide sufficient metal at places where strength is needed, and yet make it of comparatively light material.

A further object of the invention is to separate the base of the brace, so as to allow an opening between the two feet for the circulation of water, so that there will be comparatively little surface of the boiler-plate covered by the brace.

In the accompanying drawings, Figure 1 is a perspective view of our improved brace. Fig. 2 is a side view. Fig. 3 is a view looking in the direction of the arrow 3, Fig. 2. Fig. 4 is a view looking in the direction of the arrow 4, Fig. 2. Fig. 5 is a view of the blank from which the brace is made.

Referring in the first instance to Fig. 5, A is the blank, cut, preferably, from sheet-steel and of the shape shown in the drawings, having a body portion a , a base portion a' , and a head portion a'' . Extending from each side of the head portion are wings a^3 , and extending from the base are portions $b b$, which eventually form the feet of the brace. In the first operation the blank A is bent on the center line xx , so as to form the inclined portion A' of the brace, and is then bent on the lines $y y$, so as to form the feet b .

We separate the feet $b b$ of the brace, so as to form a V-shaped passage d between the feet. The height of this passage is indicated by the dotted lines, Fig. 2. When the brace is secured to the shell of the boiler, the water will freely circulate through this V-shaped passage, and thus protect the shell to a cer-

tain extent, as it is found to be objectionable to cover the surface of the boiler with a single plate, owing to the fact that the boiler is liable to burn out at this point.

The head of the brace is flattened out, as shown in the drawings, from the point c , and the wings a^3 are turned back upon the head portion of the brace, as indicated in Figs. 1 and 4, so as to give this head portion, which is perforated at $e e$, the strength desired.

The size of the brace may be varied and the shape slightly modified without departing from the main feature of our invention.

It will be seen that we can make a very substantial and stiff brace of comparatively light material, which can be readily secured in place in the boiler and the brace strengthened where necessary, and, furthermore, a comparatively small surface of the boiler-shell is covered by the feet of the brace, as these feet are made as small as possible and are divided by the channel, through which the water can freely flow.

We claim as our invention—

1. As a new article of manufacture, a boiler-brace made of a single sheet of metal bent so as to form a body portion of double thickness, a head portion of double thickness connected to the body portion by a single thickness of metal and having feet of single thickness, substantially as described.

2. As a new article of manufacture, a boiler-brace made of a single sheet of metal bent so as to form an inclined body portion of double thickness, a head portion, said head portion having wings bent upon the head portion, and having feet spread apart and forming a channel, substantially as described.

3. As a new article of manufacture, a boiler-brace made of a single sheet of metal having an inclined body portion of double thickness, a head portion of double thickness and feet extending from each side of the base of the inclined portion, the base of the inclined portion being spread apart forming a V-shaped channel between the feet, substantially as described.

4. A blank for a boiler-brace consisting of a single sheet of metal having a body portion a , a head portion a^2 , wings a^3 projecting from each side of the head portion, and portions $5\ b$ projecting at an angle from the opposite end of the body portion, substantially as described.

In testimony whereof we have signed our

names to this specification in the presence of two subscribing witnesses.

JOHN S. WORTH.

CHARLES B. FAIRWEATHER.
